UNITED STATES PATENT OFFICE.

JOSEPH KNIGHT, OF HOLYHEAD, ANGLESEY, ENGLAND.

TURBINE.

980,644.

Specification of Letters Patent.

Patented Jan. 3, 1911.

Application filed October 29, 1907. Serial No. 399,760.

To all whom it may concern:

Be it known that I, JOSEPH KNIGHT, a subject of the King of Great Britain, and residing at 4 Wesley Terrace, Holyhead, 5 Anglesey, England, engineer, have invented certain new and useful Improvements in Power-Turbines, of which the following is the specification.

The main object of this invention is to 10 construct power turbines, more particularly such as are to be driven by steam with a view to greater economy and efficiency in working, and compactness of space.

The main feature of this invention comprises an inner rotating member carried upon a shaft, and itself provided with vanes or blades around its periphery against which during any period of consecutive running the motive fluid operates in one direction of 15 flow only; and an outer rotating member which surrounds the inner member and is provided with vanes or blades at its inner and also at its outer surface against which also, respectively, the motive fluid operates 20 in one direction of flow only during any period of consecutive running; and a fixed casing which surrounds both members and has vanes or blades at its inner surface against which also during any period of 25 consecutive running the motive fluid operates in one direction of flow only. The steam (or it may be other motive fluid) enters between the inner and outer rotating members at one end, moving such members, 30 in opposite directions of rotation, and the steam passes, from between the inner and outer rotating members, in the reverse direction, between the outer rotating member and the fixed casing. The vanes which are 35 provided at the outer surface of the outer rotating member, are, of course, set the opposite way to those of the inner rotating member. The shaft of the outer rotating member is connected with the ends of such 40 member by suitable arms, disks, flanges or the like, and is hollow and acts as bearings for the shaft of the inner rotating member; and, if the turbine is to be used simply as a 45 stationary engine for ordinary purposes, the two shafts, which of course revolve in opposite directions, are suitably geared together, but, if the turbine is for use for propelling a vessel, the outer or the inner shaft, 50 as desired, may be geared, either by connecting- 55 rods, or otherwise, with a parallel shaft,

and a propeller be mounted either on the shaft of the outer or of the inner rotating member and another propeller be mounted on the parallel shaft with which the outer or inner shaft is geared as aforesaid, the 60 two propellers being thus independently driven, namely, one by the outer rotating member and the other by the inner rotating member. To enable a vessel, however, to be conveniently maneuvered, in such case, 65 two turbines are used side by side but spaced apart as required, driving four propellers. Without, in the case of a stationary turbine, gearing the shafts of the inner and outer rotating members together, the shaft of the 70 inner rotating member may be coupled on to a dynamo or other machine, and the shaft of the outer rotating member be independently coupled to another dynamo or machine. The reversing of the turbine is effected by 75 closing the steam inlet ordinarily used and the exhaust outlet ordinarily used and admitting steam between the outer rotating member and the fixed casing, in the opposite direction to that for forward running, and admitting this steam, as it passes out from between the ends toward which it is directed of the outer rotating member and the fixed casing into a special exhaust outlet through 80 which it escapes to the atmosphere or condenser. In reversing, therefore, the drive 85 is entirely through the outer rotating member.

In order that the invention may be clearly understood, and readily carried out, I will 90 now proceed to describe the features thereof which have been already described in general terms, and also other features by reference to the accompanying drawings, which illustrate, by way of example, a practical 95 application of the same, certain of the said other features forming the subject of an application for patent of the same date as this application.

Of these drawings:—Figure 1 is a longitudinal section through a turbine constructed according to this invention. Fig. 2 is a plan of the turbine with the upper half of the casing removed. Fig. 3 is a transverse section taken on line $x-x$ of Fig. 1. Fig. 4 100 is a section taken on line $y-y$ of Fig. 1. Fig. 5 is a fragmentary view partly in section and partly in elevation illustrating the application of the controlling valves. Fig. 6 105 is a bearing face view of a ring used in 110

making a steam-tight joint at an outer end face of the turbine case. Fig. 7 shows, in section, to a still larger scale, an arrangement of rings for making a steam-tight packing between the outer rotating member and the surrounding casing. Fig. 8 shows an arrangement of two pairs of turbines, of which the turbines of each pair are arranged tandem fashion, and of which the pairs are 10 adapted to independently drive twin screws and each pair to drive also through the medium of a parallel shaft, an outside screw. Fig. 9 shows an arrangement in which two turbines are adapted to independently drive twin screws, and each also to be utilized in driving an outside screw through the medium of a parallel shaft.

Referring first to Figs. 1, 2 and 3, A is the inner rotating member of the turbine 20 fixed upon a shaft A', B the outer rotating member, which is carried by a hollow shaft B' which forms the bearings for the shaft A', and C the fixed casing which surrounds the outer member. The member A is formed 25 of a number of lengths increasing in diameter toward the outflow end, but while this formation is preferred as enabling the vanes for each length to be made exactly of the same size, and enabling them to be 30 conveniently fixed, this particular formation of the member is not essential. The inner surface of the outer rotating member B is shaped to correspond with the formation of the outer surface of the inner rotating member A. Vanes project both from 35 the outer surface of each length of the rotating member A and from the corresponding lengths of the inner surface of the rotating member B, being set of course to insure that the two members will revolve in 40 opposite directions and the rings of vanes of the one member alternating with those of the other. Vanes project also from the outer surface of the rotating member B, for 45 as far back as may be required from the rear end, as shown, and corresponding vanes project from the inner surface of the casing C. For forward running, steam enters 50 through the branch C' controlled by the valve C² into a space D at the forward end D' of the rotating member B, and passing through openings c through such end enters the annular space between the inner and outer rotating members, and passing longitudinally through the space drives such 55 members in opposite directions of rotation, and passing out from between the rear ends of such members passes through openings c' of a disk E' which forms the rear end of 60 the outer rotating member, into the space E behind such disk, and then returns into the rear end of the space between the outer rotating member and the casing C, and flowing back through such space increases the propelling force tending to drive the outer ro-

tating member, and finally flows out through the exhaust branch F controlled by the valve F² and away to the condenser or atmosphere. When it is desired simply to reverse the turbine, the steam is shut off from the branch 70 C' and the outlet from the branch F is closed. Steam is then admitted through a branch G controlled by valve G² into a space around the forward portion of the outer rotating member B which is cut off from the space D, 75 and this steam flows forward through the space between the outer rotating member and the casing C, and acting upon the vanes which project from the outer surface of such member drives such member in the reverse direction of rotation. The steam used in reversing the turbine flows out from between the rear end of the outer rotating member B and the casing C into the space E aforesaid, and thence through an exhaust 80 branch G' controlled by the valve G³ to the condenser or atmosphere.

If it is desired to utilize the turbine for driving one propeller through the medium of one of the shafts and another propeller through the medium of the other shaft, an arrangement such, for instance, as shown by Fig. 8 may be adopted, in which 1 is the turbine, of which the shaft B' of the outer rotating member is coupled direct to a propeller shaft B², and of which the shaft A' of the inner rotating member is connected or geared with a parallel shaft A³ such as through the medium of three-throw cranks a' and connecting-rods a², the shaft A³ being 95 coupled direct to a propeller shaft B³. 3 is a thrust-block for the shaft B² and 4 a combined bearing and thrust-block for the shaft B'. In Fig. 8 two turbines are shown arranged tandem fashion, but of course one 100 of sufficient power may be used, if desired. The numerals 2 indicate the condensers into which the exhaust steam passes from the turbines 1. In the arrangement shown by Fig. 8, two sets of turbines arranged on opposite sides of the longitudinal axis of the vessel are shown, driving four propellers, the two sets being independent of one another; but of course a single set, or a single turbine, may be used, to drive two propellers only, arranged at opposite sides of the longitudinal axis of the vessel. The arrangement of four propellers, however, affords special facility for maneuvering. Two propellers may be used for a vessel, 110 driven, respectively, by the inner and outer rotating members of the turbine; or a single propeller may be driven by both the rotating members, the shafts of which are, for such purpose, geared together, and any desired number of propellers may be each 115 driven in this manner by its own turbine.

In the arrangement shown by Fig. 9, a single turbine 1^a is shown, having its shaft B' coupled direct to a propeller shaft B² and 120

driving, through the medium of its shaft A' and cranks and connecting-rods, a shaft A³ which is coupled to a propeller shaft B³, an auxiliary turbine 1^b, of any ordinary construction, being shown as an auxiliary for driving the shaft B. By the use of this auxiliary turbine the power used in driving the propeller shaft B³ can be made equal to that driving the propeller shaft B², the power of the outer rotary B being greater than that of the inner rotary A. The reversing may be effected by means of the auxiliary turbine and the outer rotating member of the main turbine. A second turbine 1^a and auxiliary turbine 1^b are shown as similarly driving two propeller shafts at the other side of the longitudinal axis of the vessel. A condenser 2^c is shown in connection with each set of turbines which comprise a turbine 1^a and an auxiliary turbine 1^b.

To enable the outer rotating member B to be put properly into place in relation to the inner rotating member A, and a portion 25 of such outer rotating member to be readily removed for inspection of the inner rotating member, the outer member is divided into halves longitudinally, and to enable the halves to be securely fixed together when 30 placed around the inner rotating member, such halves are formed, along the edges thereof which extend forward of the portion around which the exterior vanes of the outer rotating member are arranged, with flanges 35 a' through which the halves are bolted together; and, for additional security, the halves are held together at the rear end by a rim m of the disk or end E' which is tapered slightly inside and is tightened over a 40 correspondingly tapered portion of the rotating member B. The rings H, also, into which are fitted the vanes which project around the inside and outside of this rotating member, are each formed in halves (see 45 Fig. 4) and are securely held from turning around or within such member by forming them each with key grooves k which are slipped along over feather keys k' carried by such member.

50 A fluid-tight joint is made at each place where the shaft A' of the rotating member A passes into the hollow shaft B' of the rotating member B, by means of a packing gland M around the shaft A' which is 55 pressed, from the steam side of the joint, against the packing within the stuffing-box. Each gland, however, is held also by pins and nuts. A fluid-tight joint is made at the outer face of the fixed case, at each end, by 60 means of a faced ring N (Figs. 1 and 6) which is set up thereagainst through an elastic medium n which is applied within an annular groove of a backing-ring P, disk, or collar, which is fixed around the hollow shaft B' 65 and into which groove an annular plug n'

enters from the back of the faced ring N. The elastic medium n, which may consist conveniently of india rubber covered with asbestos, may be set up by means of set screws n⁴ screwed through the back of the 70 backing-ring P and bearing against a metal ring n² which presses against the elastic medium. Each face ring N is formed in halves, as shown by Fig. 6, to enable it to be put in place, and the halves are held together at 75 each joint by a projection such as p of the one half which is let into a corresponding opening of the other half, each projection being formed enlarged at its outer end to give it a secure hold; and the bearing surface 80 of each ring N, has, preferably, grooves n³ formed therein to reduce friction and minimize leakage.

In order to provide a fluid-tight joint or packing between the inside of the rear end 85 of the casing C and the portion of the member B which rotates therein, an arrangement, such as shown in section by Fig. 7, may be adopted. In this figure, C shows a portion of one side of the rear end of the 90 casing, and B a portion of the corresponding side of the rotating member.

R R' (Fig. 7) are sections of rings which are pushed in between the surface of the member B and the casing C. The rings R 95 are slipped over the member B, and held in place against turning in relation thereto by means of feather keys q spaced apart around the circumference of the member B, there being conveniently two of such keys spaced 100 apart at an angle of about 90 degrees; and the rings R' are slipped along inside the casing C and are prevented from turning by feather keys q' of the casing. One of the rings R' is pushed up against a shoulder r 105 of the casing, and then one of the rings R is pushed up against such ring R', and the next ring R' then pushed up against the ring R, and a further ring R pushed up against the second ring R', and so on for 110 any number of rings, but usually four rings will be sufficient. The last ring is kept in place by a plate S fixed against the end of the member B and bearing against the outer surface of the ring. The rings R of course 115 turn with the rotating member B, and are of a depth which insures that they will clear the keys q', while the rings R' are stationary and of course of a depth to insure that the keys q will clear them. The bearing 120 of the rings against one another insures the required tightness of the joint against the passage of fluid therethrough.

Having fully described my invention, what I claim and desire to secure by Letters Patent, is:

1. In rotary motors, a central revolving member, blades mounted on said member, a second revoluble member inclosing said first member, blades mounted on the interior and 130

- exterior walls of said second member, a casing inclosing said member, means for the admission of power to the interior of said casing and said second member and means for the escape of power therefrom.
2. In rotary motors, a central revoluble member, blades mounted on said member, a second revoluble member inclosing said first member, blades on the interior wall of said second member, a casing inclosing said second member, blades on the exterior wall of said second member and blades on the interior wall of said casing, means for the admission of power to the interior of said casing and said second member and means for the escape of power therefrom.
3. In rotary motors, a central revoluble member, blades mounted on said member, a second revoluble member inclosing said first member, blades of opposing pitch to said first blades mounted on the interior wall of said second member and interposed in annular series with said first blades, a casing inclosing said second member, blades mounted on the interior wall of said casing, blades of opposing pitch to said blades on said casing mounted on the outer wall of said second member and interposed in annular series with said blades on said casing, means for admitting power to the interior of said second member, means for the passage of power from said second member to said casing and means for the escape of power from said casing.
4. A power turbine having inner and outer rotating members carrying vanes or blades which project within the annular space between them, and a fixed member which leaves an annular space between itself and one of the rotating members into which blades from the fixed member and from the said rotating member project, the motive fluid having to pass in the ordinary use of the turbine endwise through both the annular spaces but in an opposite direction through the one to that in which it passes through the other.
5. A power turbine having an inner rotating member from the exterior surface of which vanes or blades project and a surrounding rotating member from the interior and exterior surfaces of which vanes or blades project, and a surrounding fixed casing from the inner surface of which vanes or blades project, the arrangement being adapted for the motive fluid to pass first endwise through the annular space between the inner and outer rotating members into which the vanes or blades of the inner rotating member and the inner vanes or blades of the outer rotating member project driving such inner and outer rotating members in opposite directions of rotation, and then to pass in the reverse direction endwise through the annular space between the outer

rotating member and the casing within which the exterior vanes or blades of the outer rotating member and the vanes or blades of the casing project, and from thence to the exhaust or condenser.

6. In rotary motors, a central revoluble member, blades mounted on said member, a second revoluble member inclosing said first member, blades mounted on the interior and exterior walls of said second member, a casing inclosing said member, means for admitting a motive fluid within said casing and said second member for driving said revoluble members, and controllable means capable of operation to reverse the direction of flow of the motive fluid within said casing for reversing the direction of rotation of one of the members.

7. A rotary motor having an inner revoluble member, a second revoluble member inclosing said first member but spaced therefrom to produce a passage for the flow of motive fluid, vanes or blades on said respective members within said passage, a casing inclosing said second revoluble member but spaced therefrom to produce a second passage communicating with said first passage and also adapted for the flow of motive fluid, vanes or blades on the casing and said second member within said second passage, means for admitting fluid under pressure to one of the passages, and means for discharging such fluid from the other passage.

8. A rotary motor having an inner revoluble member, a second revoluble member inclosing said first member but spaced therefrom to produce a passage for the flow of motive fluid, vanes or blades on said respective members within said passage, a casing inclosing said second revoluble member but spaced therefrom to produce a second passage also adapted for the flow of motive fluid, vanes or blades on the casing and said second member within said passage, means for admitting fluid under pressure to said respective passages, for driving said revoluble members in one direction, and controllable means capable of operation to reverse the direction of flow of the motive fluid in one of said passages.

9. A rotary motor having an inner revoluble member, a second revoluble member inclosing said first member but spaced therefrom to produce a passage for the flow of motive fluid, vanes or blades on said respective members within said passage, a casing inclosing said second revoluble member but spaced therefrom to produce a second passage communicating with said first passage and also adapted for the flow of motive fluid, vanes or blades on the casing and said second member within said second passage, means for supplying fluid under pressure to the motor for driving said revoluble members, and controllable means capable of oper-

ation to reverse the direction of flow of the motive fluid through one of said passages.

10. A rotary motor having a revoluble member divided longitudinally in sections provided with peripheral attaching devices, and vanes or blades carried by said member and positioned between said attaching devices.

11. A rotary motor having a revoluble member divided longitudinally in sections provided with attaching devices at their extremities, and vanes or blades carried by said member and positioned at the central part thereof between such attaching devices.

15. 12. A rotary motor having inner and outer rotating members, shafts for the respective members, the outer member being longitudinally divided in sections, and a device carried by the shaft of said outer mem-

ber and affording connection between the 20 sections thereof.

13. A rotary motor having inner and outer rotating members, shafts for the respective members, the outer member being longitudinally divided in sections, and a device carried by the shaft of said outer member and provided with a tapered rim portion engaged with the sections of such outer member to hold the same in connected relation.

In witness whereof I have hereunto signed my name this 19th day of October 1907, in the presence of two subscribing witnesses.

JOSEPH KNIGHT.

Witnesses:

ROBERT G. GROVES,
